UNITED STATES PATENT OFFICE.

ESSINGTON N. GILFILLAN, OF CHICAGO, ILLINOIS.

DESIGN FOR A THREAD CASE OR CABINET.

SPECIFICATION forming part of Design No. 27,406, dated July 20, 1897.

Application filed June 10, 1897. Serial No. 640,254. Term of patent 7 years.

To all whom it may concern:

Be it known that I, ESSINGTON N. GILFILLAN, a citizen of the United States, residing at Chicago, in the county of Cook and State 5 of Illinois, have invented and produced a new and original Design or Useful Shape for Thread Cases or Cabinets, of which the following, in connection with the accompanying drawings, is a full, clear, and exact specification.

In the said drawings, Figure 1 is a perspective view of a thread case or cabinet embodying my design, and Fig. 2 is a side elevation thereof.

15 The leading features of my design consist of a thread case or cabinet having a semicylindrical open front in which are arranged a number of vertical partitions A, arranged in a semicircular series and apparently rising 20 from a base portion B up to the band C.

The entire cabinet is round when viewed in plan, and cylindrical when viewed in side, elevation, as in Fig. 2. The intermediate portion of its rear side is composed of a number 25 of slats or corrugations D, which rise from the plain cylindrical base B and termi-

nate under the narrower band C. The band C is surmounted by a circular top E, whose edges are beveled or beaded, as shown at e, on the under side. From the center of the 30 top E rises a knob-like portion F, and to one side of which is located a plate G.

The base B is a plain band-like portion similar to band C and has a beaded foot-piece b, corresponding to the beaded edge e of the 35 top E, excepting that the beaded side is turned upwardly instead of downwardly. The front of the base B under the vertical partitions A is provided with an opening H, in which are set a pair of curved slides or doors I, each 40 having a knob i.

Having thus described my invention, what I claim as new therein, and desire to secure by Letters Patent, is—

The new and original design or useful shape 45 for a spool case or cabinet substantially as herein shown and described.

ESSINGTON N. GILFILLAN.
